UNITED STATES PATENT OFFICE.

ATHERTON D. CONVERSE, OF WINCHENDON, MASSACHUSETTS.

DRUM.

No. 832,958.

Specification of Letters Patent.

Patented Oct. 9, 1906.

Application filed February 23, 1906. Serial No. 302,454.

To all whom it may concern:

Be it known that I, ATHERTON D. CONVERSE, a citizen of the United States, and a resident of Winchendon, in the county of Worcester and State of Massachusetts, have invented a new and Improved Drum, of which the following is a full, clear, and exact description.

My invention relates to an improvement in drums, and particularly to metal toy drums.

The purpose of the invention is to construct the drum entirely of sheet metal, so that the heads can be securely attached to the shell without any intermediate props or supports being employed, the sole supports for the heads being at the edges of the chimes of the shell and from uniform contact with the inner face of the shell.

Another purpose of the invention is to so assemble the parts as to render the drum strong, durable, and economic and so that all the requisite resonant qualities are obtained, and, furthermore, to provide a drum which can be used as a receptacle for merchandise without impairing its utility as a drum.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the improved drum. Fig. 2 is a vertical section through a portion of the drum, the view being drawn upon an enlarged scale. Fig. 3 is a perspective view of the drum when employed as a receptacle. Fig. 4 is a vertical section through a portion of the drum, illustrating the manner in which the upper head is placed in the shell; and Fig. 5 is a section similar to Fig. 4, illustrating the manner in which the lower head is secured to the shell.

Referring first to Figs. 1 and 2 of the drawings, A represents the shell of the drum, and B and B' the two heads for the same, all of the said parts being made of sheet metal as thin as possible consistent with strength. Each head is provided with an outwardly-extending marginal flange 10, struck up from the head proper, and the flange of each head is pressed or otherwise brought into close and practically integral engagement with the

inner face of the shell A. The depth of the flanges 10 is such that when the heads are in position the flanges extend from the edges or chimes of the shell sufficiently far inward to bring the edges of the heads proper to a point at or near the usual beads 11, produced in the shells of such drums; but, as illustrated in Fig. 2, the heads do not enter the said beads for support. 65

The only supports necessary for the heads outside of the frictional engagement of their flanges 10 with the shell A is obtained, for example, by bending or overlapping the outer edges of the flanges 10 over the edges 70 or chimes of the shell, thereby forming continuous seams 12, which are gripped or otherwise tightly pressed to a positive gripping engagement with the shell.

The heads having been placed in position, 75 apertures 13 are made in the flanges 10 of the heads and corresponding portions of the shell A, which also tend to promote the sealing connection between the heads and the shell, and, finally, cords 14 are laced from head to head through said apertures, serving also in a measure to hold the parts in position.

I desire it to be understood that the shell may be carried over the flanges instead of being secured as shown or that the heads 85 may be secured in position by rivets, tangs, eyelets, or similar means without departing from the spirit of the invention and that the drum may be used as a receptacle for merchandise, if desired, which latter construction is shown in Figs. 3, 4, and 5 and consists as follows: A shell C is employed and two heads D and D' are fitted in the shell, but only the bottom head D' is made fast to said shell, the other head D being removable 95 therefrom, but is supported by and is in frictional engagement with the shell. Each head is provided with an outwardly-extending marginal flange 16, and when the heads are placed in position in the shell their flanges are in close contact with the inner face of the shell. The lower head D' may be secured to the shell in any approved manner, but by preference the outer edge of the flange 16 is bent over the lower chime of the shell and is crimped or clamped thereto, forming a locking-seam 17, but the chime-section of the shell may be seamed over the flange of the head, if desired. 100

In addition to the above manner of fastening the head to the shell eyeleted shanks 18 of hooks 19 are passed through the shell and

the flange 16 of the lower head 'D', being riveted or otherwise secured to place, as is shown in Fig. 5.

With reference to the upper head D its flange 5 is provided with an outwardly and downwardly turned section forming an exterior annular socket 20, which when the head is placed in position in the shell receives the upper chime of the latter, as is shown in Figs. 4 and 5. Adjacent to the upper chime of the shell C the eyeleted shanks 21 of hooks 22 are secured in the shell only, both the lower hooks 19 and the upper hooks 22 being at the exterior of the shell, and the upper hooks are in staggered relation to the lower hooks. The hooks 19 and 22 are intended as stays for the cord 23, which represents the tension-cord of a regular drum.

Having thus described my invention, I claim as new and desire to secure by Letters Patent—

1. As an improved article of manufacture, a metal drum comprising a shell, and heads having outwardly-extending marginal flanges 25 at an angle to the outer faces of the heads, means for securing the said flanges to the shell at points beyond the head and a flexible connection between the said heads.
2. As an improved article of manufacture, 30 a sheet-metal drum comprising a shell, and heads having marginal flanges, said flanges fitting against the inner face of the shell and having their edges bent over the edges of the shell and parallel with the outer face of said shell and a cord connecting the said heads.
3. As an improved article of manufacture, 35 a sheet-metal drum comprising a shell, heads

having marginal flanges, said flanges fitting against the inner face of the shell and having their edges bent over the edge of the shell 40 and parallel with the outer face of the said shell, a cord, and means at the upper and lower portions of the shell with which the cord engages.

4. As an improved article of manufacture, 45 a metal drum, comprising a shell, heads having marginal flanges fitting against the shell, the shell and flanges having registering apertures, and a cord laced through the said apertures.

5. As an improved article of manufacture, 50 a metal drum, comprising a shell, heads having marginal flanges fitting against the inner face of the shell and having interlocking engagement therewith, the shell and flanges having registering apertures, and a cord laced through said apertures

6. As an improved article of manufacture, 55 a metal drum comprising a shell and heads for the same, said heads having outwardly-extending marginal flanges which fit close to the inner face of the shell, a seam connection between the chimes of the shell and the edges of the flanges, said shell and flanges having registering apertures therein, and cords 60 laced through said apertures, extending from head to head.

In testimony whereof I have signed my name to this specification in the presence of two subscribing witnesses.

ATHERTON D. CONVERSE.
